UNITED STATES PATENT OFFICE.

JAMES A. ELDER, OF DEMING, NEW MEXICO.

AIRPLANE.

Application filed June 23, 1924. Serial No. 721,788.

To all whom it may concern:

Be it known that I, JAMES A. ELDER, a citizen of the United States, residing at Deming, in the county of Luna and State of New Mexico, have invented certain new and useful Improvements in Airplanes, of which the following is a specification.

This invention relates to airplanes. An object of this invention is to provide an improved landing gear and to provide an airplane that may alight on land or water and to provide a landing gear in which the airplane may alight on a rough and uneven surface and which is flexible at various points. A further object of this invention is to provide a landing gear of a type which is adapted to carry the plane over muddy ground or soft sand with a minimum of resistance, whereby the plane may arise or alight in places heretofore thought impossible. A further object of this invention is to provide a landing gear which may be withdrawn and flexed in such a manner as to provide a minimum of head resistance. A further object of this invention is to provide a landing gear adapted to land at higher velocities and one which is adapted to act as a superior shock absorber. With these and other objects in view the invention consists in the construction, the combination, the detail and arrangement of parts as hereinafter more fully described and claimed.

In the drawings;

Figure 1 is a side elevation partly fragmentary;

Figure 2 is a fragmentary front elevation of Figure 1;

Figure 3 is a bottom plan view partly fragmentary of Figure 2;

Figure 4 is a fragmentary front elevation of a modified form;

Figure 5 is a fragmentary longitudinal section of a further modification.

In the present embodiment of my invention, I provide a belt 2 carried by a plurality of wheels, 3, 4, 5, 6, 7, 8 and 9, the wheels being carried by an articulated member 10 comprising the sections 11 and 12 having adjacent ends pivotally connected, as at 13, said pivot 13 constituting 11 and a minor section 12, the flexing being pivotally at 13 on the axis of the wheel 4 and the section 12 being pivotally connected, as at 15, to a standard 14. A link 16 is pivotally mounted at 17 to a standard 18 and

pivots on each side of the belt and is carried in pairs on each side of the fuselage of the airplane. Pivotally mounted to the section 12 is a link 19 carrying a belt tightener roll 20 yieldingly held against the belt 2 by a spring 21. The bar 11 carries pivotally mounted thereto on the axis of the wheel 6 a link 22 penetrating internally and carrying a helical spring 23, the spring 23 and link 22 being carried by a crank 24, the crank 24 pivotally mounted at 25 and 70 provided with a handle 26 and movable over an arcuate rack 27. In operation it will be observed that by rearwardly moving the handle 26 upon its pivot that it will automatically cause the links 16 and 12 to be drawn upward toward the body of the plane and retract the landing gear into the dotted lines position shown in Figure 1. It will further be observed that upon striking the ground that the gear will tend to flex upon its pivot 13 against the yielding of the spring 23 and that owing to the several pivots involved that there will be a yielding in various places and a combined uniform and easy cushioning effect. In traveling along the ground it will be observed that an endless tread effect is had.

By reference to Figure 4 it will be seen that I may carry mounted to the side of the bars 11, a pair of floats 28 which floats 90 may be of light metal or may be rubber bags blown up and carried by light wires in the form of a frame or netting. In the specific means of mounting my landing spring as shown in Figure 6, the bar 22 carrying the 95 spring 23 is provided with a nut 29 and a sliding collar 30, which sliding collar 30 is carried by the arm 24, the collar 30 being normally held by a nut 31 whereby, on adjusting the tension of the nut 29, the tension of the spring 23 may be regulated.

While I have disclosed certain specified and preferred forms of invention, it is obvious that my invention is not limited thereto and that other expedients may be used 105 within the spirit and scope of this invention.

Inter-connecting the lever 26 with a lever 32 is a flexible element 33, the lever 32 being pivotally mounted at 34 and carrying a brake shoe 35, adapted to engage the wheel 110 3, whereby, the brake may cooperate with the lever 26 in locking the movement of the

2
plane upon the flexing of the section 11 to a predetermined position.

Claims:

1. In combination, a hand crank, a landing gear, means interconnecting the crank and landing gear for varying the position of the gear and a brake for the landing gear, the brake operable by the varying means. 65
2. In combination, with an airplane, a pair of depending links inclined backward and spaced one forward of the other, a bar inter-connecting the links and carrying a plurality of wheels, a belt passing around the wheels and a belt tightener carried substantially at the union of the forward link and bar. 70
3. In combination, an airplane, an endless tread landing gear, a link, a lever, a spring carried by the link, the link engaging the landing gear and provided with a shoulder adapted to engage the spring, a collar carried by the link engaging the other end of the spring and mounted on the lever. 75
4. A landing gear for an airplane comprising an articulated member comprising two pivotally connected sections, means for pivotally connecting one of said sections to the airplane, a link connected to the airplane and to the second section of the member, an endless tread member operatively engaged with the sections of the member, and means for swinging the member toward the airplane or in the opposite direction, the sections of the member when in the second position being angularly related. 80
5. In combination with a fuselage of an airplane, an articulated member comprising two pivotally connected sections, means for pivotally connecting one of the sections to the fuselage, a link connected to the fuselage and to the second section, an endless tread member carried by the sections of the member, and means yieldably engaged with the second section of the member for yieldingly supporting the same spaced from the fuselage and in angular relation with the first section of the members. 85
6. In combination with a fuselage of an airplane, an articulated member comprising two pivotally connected sections, means for pivotally connecting one of the sections to the fuselage, a link connected to the fuselage and to the second section, an endless tread member carried by the sections of the member, and means yieldably engaged with the second section of the member for yieldingly supporting the same spaced from the fuselage and in angular relation with the first section of the member, said means being also operable to hold the member closely adjacent to the fuselage. 90
7. In combination with a fuselage of an airplane, an articulated member comprising two pivotally connected sections, means for pivotally connecting one of the sections to the fuselage, a link connected to the fuselage and to the second section, an endless tread member carried by the sections of the member, and means yieldably engaged with the second section of the member for yieldingly supporting the same spaced from the fuselage and in angular relation with the first section of the member, and means under control of said last named means for braking the tread member. 95
8. In combination with a fuselage of an airplane, a landing gear therefor comprising an articulated member consisting of two pivotally connected sections, means for pivotally connecting the sections of the member to the fuselage, means coacting with one of the sections for yieldably holding the same away from the fuselage with the other section angularly disposed with respect to the fuselage. 100
9. In combination with a fuselage of an airplane, a landing gear therefor comprising an articulated member consisting of two pivotally connected sections, means for pivotally connecting the sections of the member to the fuselage, means coacting with one of the sections for yieldably holding the same away from the fuselage with the other section angularly disposed with respect to the fuselage, said second section being disposed forwardly of the fuselage. 105
10. In combination with a fuselage of an airplane, a landing gear therefor comprising an articulated member consisting of two pivotally connected sections, means for pivotally connecting one of the sections to the fuselage, said sections being disposed forwardly of the fuselage, a link operatively connecting the second section of the member to the fuselage, and yieldable means carried by the fuselage and operatively engaged with the second section of the member for swinging the member toward or from the fuselage. 110
11. In combination with a fuselage of an airplane, a landing gear therefor comprising an articulated member consisting of two pivotally connected sections, means for pivotally connecting one of the sections to the fuselage, said section being disposed forwardly of the fuselage, a link operatively connecting the second section of the member to the fuselage, and yieldable means carried by the fuselage and operatively engaged with the second section of the member for swinging the member toward or from the fuselage and to maintain said member in either of two such positions. 115

In testimony whereof I affix my signature.

JAMES A. ELDER.
